US00D815299S

(12) **United States Design Patent** (10) **Patent No.:** **US D815,299 S**
(45) **Date of Patent:** **** Apr. 10, 2018**

(54) **REAGENT KIT WITH MULTIPLE BOTTLES**

(71) Applicant: **Abbott Laboratories**, Abbot Park, IL (US)

(72) Inventor: **Robert Paul Luoma, II**, Colleyville, TX (US)

(73) Assignee: **ABBOTT LABORATORIES**, Abbott Park, IL (US)

(**) Term: **15 Years**

(21) Appl. No.: **29/531,426**

(22) Filed: **Jun. 25, 2015**

Related U.S. Application Data

(63) Continuation of application No. 13/801,154, filed on Mar. 13, 2013.

(57) **CLAIM**

The ornamental design for a “reagent kit with multiple bottles,” as shown and described.

DESCRIPTION

FIG. 1 is a front right perspective view of a reagent kit with multiple bottles.

FIG. 2 is a front view of the reagent kit of FIG. 1.

FIG. 3 is a right side view of the reagent kit of FIG. 1.

FIG. 4 is a left side view of the reagent kit of FIG. 1.

FIG. 5 is a top view of the reagent kit of FIG. 1; and,

FIG. 6 is a bottom view of the reagent kit of FIG. 1. The features shown in broken lines form no part of the claimed design.
